CLAIM

The ornamental design for a carabiner with pivoted gate, as shown and described.

DESCRIPTION

FIG. 1 is an isometric view from the upper right front of a carabiner with pivoted gate, including my new design;

FIG. 2 is a right side elevational view thereof;

FIG. 3 is a top plan view thereof;

FIG. 4 is a bottom plan view thereof;

FIG. 5 is a front end elevational view thereof; and,

FIG. 6 is a left side elevational view thereof.

The broken lines in FIGS. 1-6 bounding the shaded areas represent the bounds of the claimed design, while all other broken lines showing portions of a tool handle in which the carabiner is mounted are included merely to show the environment for illustrative purposes and form no part of the claimed design.
